UNITED STATES PATENT OFFICE.

THERON McCAMPBELL, OF HOLMDALE, NEW JERSEY.

GARMENT PATTERN.

Application filed December 14, 1922. Serial No. 606,803.

The present invention relates to certain new and useful improvements applicable to tailors' guides, garment makers' templets and patterns, but more particularly useful and valuable in connection with the cheap patterns generally made of paper and sold in great numbers to dress-makers and to women generally for use in the shaping and assembling of garments of all kinds.

10 In a copending application for patent Serial No. 606,802, filed Dec. 14, 1922, I have described and claimed a system of patterns whereby a single sheet is made to serve for outlining a plurality of sizes of garment of 15 a given design. But, in the great majority of cases, the outline of a pattern is only a part of the means of guidance requisite. Most garment patterns must be furnished with printed or perforated indications whereby 20 the user may know how to tuck, pleat, hem, shirr, smock or fold the material after it is cut out; and, if it be sought to include indications of these kinds for a multitude of sizes 25 all on a single pattern sheet, the confusion becomes such as to make the pattern quite useless to unprofessional users, and of small relative value even to professionals.

The present invention supplies an economical simple solution of this problem; furnishing a pattern capable of ready use without the least confusion by unprofessional women in making garments of any desired standard size from a single pattern, together with its tucks, pleats, hems, shirring, smocking 35 etc., all in their proper places for the different sizes.

This end is accomplished by using, in combination with the main pattern sheets which disclose the outlines of each garment part, one or more auxiliary strips (which may be 40 straight or curved) bearing guiding lines, words, numbers and other marks having reference to the folding operations (such as tucking, pleating etc.). When the cloth has been 45 cut from the main sheet, the auxiliary strip or strips is or are laid across it, and, when pinned or tacked in place, the guides on the strip indicate exactly where the folds are to be made in the cloth and how the cloth 50 is to be sewed etc. to produce the effect desired. It is only necessary, then, to fold the cloth and the paper together, while lying flat the one against the other, the folds being produced just where indicated on the auxiliary strip by lines, perforations etc.

This being done, the pins or other tem-

porary fastenings are removed, and the paper can be taken away, leaving the garment folded behind it. This can, of course, be accomplished little by little, if desired; and it 60 may be done with a half width pattern or a whole width pattern.

In commercial practice the auxiliary strips 65 may be sold with the corresponding main sheets, either already separated, or, what is better, forming removable edges of the sheets with which they are to be used.

From this it is clear that, a single main sheet, printed or perforated with outlines for a number of different sizes may be provided 70 with as many auxiliary strips as there are sizes, (or two or more for each size), each strip bearing properly located guiding marks for locating the folds, tucks, etc. for the size to which it belongs. Identifying marks on 75 the strips and main sheet outlines will indicate with which main outline each strip is to be used.

The invention is illustrated in the accompanying drawings in connection with a main 80 pattern sheet for one part of a garment, marked for three sizes. Only three sizes are indicated for greater clearness in the drawing, although it is to be understood that the invention may be applied to patterns for 85 only one size or for as many sizes as are found convenient. Also the outlines etc. may be either perforated or printed, although the latter, as illustrated, is preferred, since, among other advantages, it permits both sides 90 of a pattern sheet to be separately used, thus permitting the display of a greater number of sizes than otherwise possible.

In the accompanying drawings Fig. 1 shows the mere outline of a plain skirt pattern for three sizes, having integral folding or auxiliary strips, Figs. 2, 2^a and 2^b show the separate strips with their more essential markings all on a larger scale than Fig. 1, Fig. 3 shows the mode of folding the strips 100 and dress material together preparatory to either tucking or pleating, Fig. 4 shows the final pressed and sewed arrangement for a box pleat and Fig. 5 shows the pressed and sewed arrangement for a plain pleat.

105 It is to be understood that these figures are merely explanatory of the principles of the invention, and that the actual proportions and locations of guide lines shown are not intended to be correct in any given pattern. In other words no attempt is here made to show a properly graded pattern for actual

use, as this is a matter within the province of those skilled in the art. Also it is to be understood that, although, for great clearness and simplicity, only one auxiliary strip 5 is shown for each size in the drawing, the invention applies to patterns in which, for instance, two strips are given for each size, one for folding, hemming etc. at the top and the other at the bottom. In other words, the 10 number of strips supplied for each size is not an essential of the invention.

The patterns made in accordance with this invention may be either full size; or, as is frequently the case in present practice, they 15 may correspond to one half of the symmetrical garment part for which each is intended. The auxiliary strips, too, may be less than full length, without departing from the invention, although these are preferably 20 made the full length, so that they can be folded in with the entire garment part when cut out. In the drawing, Fig. 1, the main sheet is shown one half width and the auxiliary strips full length.

25 In Fig. 1, the main half width sheet for a pleated skirt pattern is shown bounded on one side by the center fold line 10, and on the opposite side by the line 11 corresponding to the largest sized skirt contemplated. The 30 line 12 indicates the next smaller size and the line 13 the smallest of the three sizes intended. These lines limit the fullness or circumference of the skirt. Its length is determined by the dressmaker in each case, according 35 to the height of the person for whom it is intended.

The auxiliary strips for guiding the shaping (tucking, pleating etc.) of the skirt are 40 shown in Fig. 1 as made in one piece with the main sheet. The strip 14, for the largest size is twice as long as the width from 10 to 11 (being the width of the half size main pattern sheet). Similarly the strip 15 for the 45 next smaller size is twice the width from 10 to 12; and the strip 16 for the smallest size is twice the width from 10 to 13.

It will, of course, be understood that as 50 many sizes as are convenient may be shown (each with its appropriate auxiliary strip or strips) and the three sizes shown are merely 55 illustrated by way of example. Also, a number of sizes may be shown on each side of the main sheet, thus increasing the usefulness of the single piece of paper.

55 The drawings have been made as simple as possible for clearness, but it will, of course, be understood that, such notches, perforations, words, lines or signs may be used on the pattern as may be found convenient, and 60 as is well understood by those skilled in the art.

Each auxiliary strip, too, may bear words, letters, signs etc. giving any desired information and directions for use. Most of these 65 have been omitted from the drawings, but in

Figs. 2, 2^a and 2^b the dotted lines 17, 18 are shown, indicating the points in the material which come together when folds are made along the lines 19 indicated by rows of crosses, in forming tucks and pleats. The longitudinal double arrows are conventional signs indicating that the lines 17 and 18 at their respective extremities come together in the shaping of the garment. It will be noticed that the spacing of the various lines in the 75 different strips varies, so that pleats of different appropriate size and spacing may be produced for the different sizes of skirt.

The skirt having been cut out in the full size desired by means of the main sheet, the auxiliary strip corresponding to that size is laid across it transversely to the lines of the desired folds, and is pinned or "tacked" down on the cloth. The material is then folded, together with the strip, in the manner indicated, with respect to two folds, in Fig. 4. In Fig. 3 the strip is indicated edgewise, by the dotted line, and the locations of the guiding lines are shown respectively by the numerals 17, 18 and 19, corresponding to Figs. 90 2, 2^a and 2^b.

The cloth having been thus folded all the way across in contact with the guiding strip pinned or tacked to it, the folds are secured by stitches at intervals and the paper is removed, 95 being capable of repeated use, if desired.

The mode of pressing the folds will vary according to the final effect desired. If pressed as in Fig. 4, a box pleat will result. In Fig. 5 is shown a simple pleat. Obviously 100 other well known shaping and folding effects may be produced by using appropriately marked auxiliary strips.

The strips may either be supplied commercially forming an integral part of the 105 main sheet, as in Fig. 1, or they may be supplied already separated, usually folded in with the main sheet in the same envelope with it.

The system above described can, of course, 110 be used with a pattern for only a single size, such as is already in common use. It has certain advantages, in any case, quite aside from avoidance of the great confusion which would 115 result from trying to indicate the differently located folds etc. for a number of sizes on one main sheet. Hitherto it has been necessary to stitch or mark through perforations in the pattern onto the cloth, and such markings require time and care in making and trouble in 120 removing them afterward. Besides it is detrimental to delicate fabrics to be obliged to use chalk marks, pin holes, etc. upon them. All this is avoided by the present invention. Another advantage of using auxiliary folding strips with a one-sized garment pattern is 125 that it makes it possible, by supplying a number of strips, to select any one of a number of kinds, sizes or relative locations of folds, tucks etc.

Moreover, where half width patterns are used symmetrically, the cloth is folded before cutting, and the marks must either be carried through both thicknesses of cloth, or the pattern must be applied twice—once reversed—so that any printed signs must be read through the paper. This is a frequent source of inaccuracy and mistakes.

What is claimed is—

- 10 1. In a pattern for a garment part, a sheet bearing the outline of a garment part of a specific shape and size, in combination with an auxiliary strip bearing guiding marks adapted, when laid on said outlined garment part, to indicate where the required folds are to be made on that specific size and shape of part.
- 15 2. Means for insuring the proper folding of a shaped garment part of a specific shape

and size comprising a strip of material adapted to be folded with said garment part, said strip bearing guiding marks so located as to clearly indicate to a dressmaker the location of the folds required by said specific shape and size of garment part.

20 25 3. As an article of manufacture, a sheet of easily foldable paper having printed upon it the outlines of garment parts of specific sizes and also having printed upon it the outlines of guiding strips each bearing guiding marks adapted to clearly indicate to a dressmaker the location of the folds required in garment parts shaped like the respective outlines of garment parts on the same sheet.

30 35 In testimony whereof I have hereto set my hand.

HERON McCAMPBELL.
